VALVE SPRING COMPRESSOR

Ira J. Clark, Fort Morgan, Colo.

Application June 14, 1937, Serial No. 148,141

5 Claims. (Cl. 29—86.3)

This invention relates to a valve spring compressor for internal combustion engines.

With the modern type of automotive engine, exceedingly stiff valve springs are employed to accommodate the high speed of the engines. It is very difficult to compress these springs sufficiently to allow removal and replacement of the valve stem keys necessary for removing and replacing the valves.

10 The principal object of this invention is to provide a compressor for this type of work which can be easily operated against the extreme pressures exerted by modern springs; which can be used and operated in a very limited space so 15 that it can be employed on the engine without removing the latter from the surrounding chassis; which will positively support the spring at any point during the compression thereof without danger of release; which can be easily 20 inserted in the very small space remaining between the valve spring washer and the tappet bearing of an engine; and which can be reversed and used either side up to void interferences around the motor.

25 Other objects and advantages reside in the detail construction of the invention, which is designed for simplicity, economy, and efficiency. These will become more apparent from the following description.

30 In the following detailed description of the invention reference is had to the accompanying drawing which forms a part hereof. Like numerals refer to like parts in all views of the drawing and throughout the description.

35 In the drawing:—

Fig. 1 is a side elevation of the improved valve spring compressor in the closed position.

Fig. 2 is a plan view thereof.

40 Fig. 3 illustrates the compressor being inserted for compression of the valve spring.

Fig. 4 is a similar view illustrating the spring in the compressed position.

Fig. 5 is a rear end view of the device of Fig. 1.

Fig. 6 is a front end view thereof.

45 In the drawing typical parts of an automotive engine are indicated as follows: valve stem 10, valve spring 11, valve tappet 12, valve tappet bearing 13, and valve spring cup 14.

The improved compressor comprises a first 50 arm consisting of two similar side members 15, bent at their one extremity at a downward angle as indicated at 16, and terminating in flanged ends forming valve spring shelves 17. A second arm 18 cooperates with the first arm 15. The 55 second arm also consists of two similar side

members which are also bent downward at their one extremity and flanged to form flanged shelves 19.

The second arm 18 is bent at a more gradual angle than the first arm 15, so that the flanged 5 extremities contact at the extreme end to facilitate insertion.

The arm 18 is joined to the arm 15 at their rear extremities by means of a pair of short links 20, preferably positioned on the outside of the 10 arms. The links are joined to the arm 18 by means of a suitable attachment bolt 21 which passes through both links and both side members and through a separating sleeve 22 which holds the arm members in their proper spaced relation. The upper extremities of the links are secured to the rearward extremity of each of the arms 15 by means of a rivet 23a. The rivets 23a 15 also secure a U-shaped frame member 23 to the arm 15. 20

Forwardly of the links 20, the two arms are hingedly secured together by means of a pair of long links 24, preferably positioned inside of the arm members. The long links 24 are secured to the arms by means of suitable hinge bolts. One 25 bolt, 25, passes through the two arm members 15 and the two links 24 and through a spacing sleeve 27. The other bolt 26 passes through the two arm members 18, the two links 24, and through the forward extremity of a threaded jack 30 screw 28. 30

The rearward extremity of the jack screw 28 passes through the frame member 23 to receive a hand nut member or threaded wheel 29 which acts through a suitable bearing washer 30 35 against the frame member 23.

The forward extremity of the arm members 15 are forced outwardly by means of a compression spring 30 surrounding an adjusting bolt 31, by means of which, any desired separation may be 40 had of the jaws to accommodate spring washers 14 of any desired diameter.

In use, the device is collapsed to the position of Fig. 1 and the arms 17 and 19 are forced between the tappet bearing 13 and the spring washer 14, as shown in Fig. 3. The hand nut 29 is now rotated to thread the nut along the shaft 28. This exerts a pressure on the frame 23 which forces the arm member 15 forwardly. The forward motion of this arm is translated by the 45 links 20 and 24 into an upward movement of the forward extremity of the arm 15 which acts to raise the valve spring washer 14 and compress the spring 11. 50

The compression can be stopped at any desired 55

point which will allow convenient removal of the spring retaining keys with assurance that the spring will be held compressed until the hand nut 29 is again rotated to again lower the arm 15.

5 As illustrated in Fig. 3, the compressor is inserted while extending at a downward angle. In some cases where this is not possible, the entire device can be reversed so that the arm 18 becomes the upper member, in which case it will 10 function with equal satisfaction.

15 By forming the links 24 longer than the links 20, the forward extremities of the arms are caused to separate very rapidly whereas the rearward extremities of the arms separate but slightly. The frame member 23 is hinged to the arm so that it can accommodate the change of angle 20 of the jack screw.

25 While a specific form of the improvement has been described and illustrated herein, it is desired to be understood that the same may be varied, within the scope of the appended claims, without departing from the spirit of the invention.

Having thus described the invention, what is 25 claimed and desired secured by Letters Patent is:—

30 1. A valve spring compressor comprising: a first and upper arm member; a second and lower arm member, said arm members being bifurcated at their one extremity; supporting flanges extending inwardly from the furcations of said latter extremities; a short link member hinged to and connecting said arm members adjacent their other extremity; a long link member hinged to 35 and connecting said arm members intermediate said first link member and said furcated extremities; a tension member extending diagonally from the lower hinge point of said long link to the upper hinge point of said short link; and means for drawing upon said tension member to swing 40 said links and cause said arm members to separate.

45 2. A valve spring compressor comprising: a first arm member; a second arm member, said arm members being bifurcated at their one extremity; supporting flanges extending inwardly from the furcations of said latter extremities; a short link member connecting said arm members adjacent their other extremity; a long link member connecting said arm members intermediate 50 said first link member and said furcated extremities; a threaded shaft connected at one extremity to one end of one of said arm members; and a nut on said threaded shaft acting against the other extremity of the other arm member to force 55 said two arm members to separate.

3. A valve spring compressor comprising: a first arm member; a second arm member, said

5 arm members being bifurcated at their one extremity; supporting flanges extending inwardly from the furcations of said latter extremities; a short link member connecting said arm members adjacent their other extremity; a long link member 10 connecting said arm members intermediate said first link member and said furcated extremities; a threaded shaft connected at one extremity to one end of one of said arm members; a nut on said threaded shaft; and a pivoted frame member secured to the other end of the other arm member for receiving the thrust of said nut so as to force said two arm members to separate.

15 4. A valve spring compressor comprising: a first arm formed of a pair of side members spaced from each other; work engaging means on one extremity of said first arm; a second arm, said second arm also consisting of two side members spaced from each other; work engaging means on one extremity of said second arm in cooperative 20 relation with the work engaging means on the first arm; a pair of short links hinged between said two arms at the extremity opposite the work engaging means; a pair of longer links; a hinge pin securing said longer links to the members 25 of said second arm, the other extremity of said longer links being hinged to the members of said first arm; a jack screw extending from about said hinge pin at a diagonal to and between the side members of said first arm; a pressure 30 member on the first arm; and a nut threaded on said screw and acting against said pressure member to force said first arm forwardly over said second arm to swing said links about their pivot extremities.

35 5. A valve spring compressor comprising: a first arm formed of a pair of side members spaced from each other; work engaging means on one extremity of said first arm; a second arm, said second arm also consisting of two side members spaced from each other; work engaging means on one extremity of said second arm in cooperative 40 relation with the work engaging means on the first arm; a pair of short links hinged between said two arms at the extremity opposite the work 45 engaging means; a pair of longer links; a hinge pin securing said longer links to the members of said second arm, the other extremity of said longer links being hinged to the members of said first arm; a pressure member hinged to and extending between the extremities of the side 50 members of the first arm; a threaded shaft mounted at its one extremity on said hinge pin and extending diagonally rearward through said pressure member; and a nut on said threaded shaft acting against said pressure member to draw said hinge pin toward said pressure member.
